UNITED STATES PATENT OFFICE.

ERNST TEUBNER, OF HOHENNEUENDORF, NEAR BERLIN, GERMANY.

AUTOMATICALLY-ACTING SAFETY DEVICE FOR USE IN CONNECTION WITH CARBURETORS OF MOTOR CARS, MOTOR BOATS, AND FLYING MACHINES.

1,408,233.

Specification of Letters Patent. Patented Feb. 28, 1922.

Application filed July 30, 1921. Serial No. 488,585.

(GRANTED UNDER THE PROVISIONS OF THE ACT OF MARCH 3, 1921, 41 STAT. L., 1313.)

To all whom it may concern:

Be it known that I, ERNST TEUBNER, a citizen of the German Republic, and a resident of Hohenneuendorf, near Berlin, Germany, 5 have invented a certain new and useful Improved automatically-acting safety device for use in connection with the carburetors of motor cars, motor boats, and flying machines, (for which I have filed application in 10 Germany, March 11, 1920,) of which the following is a specification.

This invention relates to a safety-device which operates automatically in the case of a carburetor catching fire. This is in most 15 cases a consequence of the explosion of the cylinder-contents acting also in the reverse direction and getting propagated into the suction pipe, if the suction valves of the motor close but badly, so that the fuel boiling 20 out of the carburetor in burning state runs into the body of the car or boat or the like and ignites the oily or fatty spots whereby the fire may easily spread. The driver or 25 pilot is in such a case but rarely in the position to prevent the fire from spreading and to save the car or boat or flying machine, as well as himself.

The novel device does not prevent, it is true, the fuel from escaping from the carburetor and a flame from arising, but the 30 fire is prevented from spreading in that the burning benzine is caught up and kept off the easily burning parts of the car or the like. For this purpose a tube closed by a 35 diaphragm of easily burning or melting material, such as celluloid or the like, is arranged laterally with respect to the longitudinal axis of the motor car, motor boat or flying machine (not shown). In the case of 40 the carburetor catching fire the burning benzine is caught up by a tray- or trough-shaped catcher arranged below the carburetor and the diaphragm and extending obliquely with respect, and in the direction, to 45 this latter. Owing to the diaphragm being then destroyed, a system of levers connected with it and being under the pull of a spring is released whereby the fuel cock is closed. At the same time the flame that has arisen 50 is deviated outwards through the sucking effect arising in said tube.

In order to make my invention more clear, I refer to the accompanying drawing, which shows, by way of example, one form of con-

struction of my invention, partly in side view and partly in vertical section.

a is a tube having at its free end an elbow *b* which projects laterally through the body or hull of the vehicle (not shown). The tube *a* is closed by a diaphragm *c* which is attached to a sleeve *d*. The sleeve is exchangeable and is connected with the tube *a*, in the example shown, by a transverse pin *e*. Instead of this means of connection, the sleeve may be secured, in place by screw-threads or 65 a bayonet-closure or another equivalent means.

f is lever which is connected by a screw *g* with the diaphragm *c*. Its vertical arm contacts with a roll *p*. The free end of the lever *f* is connected with a wire-rope *h* passing through a tube *i* supported from the tube *a* by standards *k*. The other end of the wire-rope *h* is connected with a lever *l* affixed to the benzine cock *m*. The lever *l* is under the 75 pull of a spring *n* arranged in a casing *o* covering the lever and the cock.

Below the diaphragm *c* is a tray or through-shaped catcher *q* which is inclined in the direction to the diaphragm. The cock *m* and the carburetor *s* are connected with 80 each other by a pipe *r* which extends through said catcher *q*.

t is a star-shaped small piece of celluloid which is attached to the diaphragm *c* and is 85 held in place by the lower end of the lever *f*.

Burning benzine escaping from the carburetor *s* is caught up by the catcher *q* upon which it runs down to the diaphragm *c* where it ignites the celluloid *t*. This burns 90 at once, the diaphragm is destroyed, and the lever *f*, thus, is no longer retained in vertical position because the spring *n* is now free to turn the lever *i* and to close the cock *m* whereby the connection between the benzine 95 tank and the carburetor is interrupted. And owing to the wide tube *a* being now open, the flame is sucked away through it, to the outside of the body or hull where it cannot do harm.

The device is adapted to be mounted upon a bracket or the like (not shown) attached in any suitable manner to the body of the car or the hull of the boat or flying machine.

Having now described my invention, what I desire to secure by a patent of the United States is:

1. An automatically operating safety de-

vice intended for use in connection with carburetors that have caught fire, comprising a tube adapted to have one end arranged below and in proximity to the carburetor, a 5 diaphragm consisting of an easily destroyable material, closing said end of said tube, a lever connected with the diaphragm, a fuel cock, another lever affixed to the fuel cock, a connection between said levers, and means 10 adapted to turn the second-mentioned lever and close the fuel cock instantly after said diaphragm has been destroyed by burning fuel.

2. An automatically operating safety device 15 intended for use in connection with carburetors that have caught fire, comprising a tube adapted to have one end arranged below and in proximity to the carburetor, a diaphragm consisting of an easily destroyable material, closing said end of said tube, a catcher inclined toward said diaphragm, a lever connected with the diaphragm, a fuel cock, another lever affixed to the fuel cock, a connection between said levers, and 20 means adapted to turn the second-mentioned lever and close the fuel cock instantly upon the destruction of said diaphragm by burning fuel.

3. An automatically operating safety device 30 intended for use in connection with carburetors that have caught fire, comprising a tube adapted to have one end arranged below and in proximity to the carburetor, a diaphragm consisting of an easily destroyable material, closing said end of said tube, a star shaped piece of an easily burning material attached to said diaphragm, a lever connected with the diaphragm, a fuel cock, another affixed to the fuel cock, a connection 35 between said levers, and means adapted to turn the second-mentioned lever and close the fuel cock instantly, after the diaphragm has been destroyed by burning fuel.

4. An automatically operating safety device 45 intended for use in connection with carburetors that have caught fire, comprising a tube, a diaphragm consisting of an easily destroyable material, closing one end of said tube, a star shaped piece of an easily 50 burning material attached to the diaphragm, a burning fuel catcher inclined toward said diaphragm, a lever connected with the dia-

phragm, a fuel cock, another lever affixed to the fuel cock, a connection between said levers, and means adapted to turn the second-mentioned lever and close the fuel cock instantly upon destruction of the diaphragm by burning fuel.

5. In a device of the character described, the combination with the carburetor of an 60 internal combustion engine, of a fuel feed-line to said carburetor, means for catching burning fuel escaping from said carburetor, means for automatically shutting off the supply of fuel to said feed-line and an inflammable member adjacent said catching means adapted to be destroyed by said burning fuel, the destruction of which permits of the operation of said shut-off means.

6. In a device of the character described, 70 the combination with the carburetor of an internal combustion engine of a fuel feed-line to said carburetor, means for catching burning fuel escaping from said carburetor, and means for shutting off the supply of 75 fuel thereto comprising a normally open shut off valve, an operating lever therefor held under tension, and an inflammable member adjacent said catching means adapted, when ignited by said burning fuel, to 80 release said lever.

7. In a device of the character described, the combination with the carburetor of an internal explosion engine, of a fuel feed line to said carburetor, means for catching 85 burning fuel escaping from said carburetor, and means for automatically shutting off the fuel supply and carrying away the burning fuel comprising a hollow tube having one end adjacent the fuel catching means, and 90 an inflammable member located adjacent said end, a shut off valve on said feed line under tension when open, levers connected to said valve and inflammable member respectively, and a connection between said 95 levers normally holding said shut-off valve open, the ignition of said inflammable member permitting the operation of said levers.

In testimony whereof I affix my signature in presence of two witnesses.

ERNST TEUBNER.
